UNITED STATES PATENT OFFICE.

FRANK I. MACAULEY, OF SAN FRANCISCO, CALIFORNIA.

DESIGN FOR A BADGE.

48,944.

Specification for Design.

Patented Apr. 25, 1916.

Application filed June 2, 1914. Serial No. 842,400. Term of patent 3½ years.

To all whom it may concern:

Be it known that I, FRANK I. MACAULEY, a citizen of the United States, residing in the city and county of San Francisco, State of California, (whose post-office address is 279 Tenth avenue,) have invented a new, original, and ornamental Design for Badges, of which the following is a specification, reference being had to the accompanying drawings, forming part thereof.

My design relates more particularly to a series of base ball bats radiating from a center in the form of a fan; having a representation of a base ball superimposed upon the fan.

I claim:

The ornamental design for a badge as shown and described.

In testimony whereof, I have hereunto set my hand this eighteenth day of May 1914.

FRANK I. MACAULEY.
